UNITED STATES PATENT OFFICE.

ERNEST A. BOHLMAN, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

LIGHTING AND IGNITION SWITCH.

Application filed November 26, 1924. Serial No. 752,296.

My invention relates to electrical switches in general and has to do more particularly with switches for controlling a plurality of circuits and the present embodiment of my invention is for use in connection with ignition and lighting circuits for automobiles or the like. It is an object of my invention to produce an improved device of the class described which embodies desirable features and advantages, all in a simple and efficient manner, and a feature of my invention is the provision of novel means for associating the actuating levers of the lighting and ignition units of the switch with the rotor elements of the lighting and ignition units, against lateral movement, and to secure the parts together which comprise the rotor elements that form the rotatable units, which units are held together without the aid of complicated fastening means such as nuts and threaded members.

Another feature of my invention is the provision of a novel method of holding the rotor elements of the lighting and ignition units in their different operative positions, and the means for producing a snap action of the rotor elements as they are moved to their different operative positions.

Another feature of my invention is the provision of a novel contact arrangement supported in the base of the ignition and lighting switch which cooperates with the wipers of the respective rotor elements, which elements when rotated cause said wipers associated with the rotor elements to engage the stationary contacts secured in the base of the switch.

Still another feature of my invention is the provision of an inter-changeable cowl light unit and horn button unit either of which may be associated with the switch without replacing parts of the switch to make the same adaptable for either the cowl unit or the horn unit, and the means for using the same spring and contact combination for both.

Another feature of my invention is the method I provide for fastening the switch to the dash of the car.

A still further feature of my invention is the provision of means for carrying the fuses, both the fuse in use and the reserve fuse.

The above features as well as others will be more fully hereinafter described, and for a

complete understanding of my invention reference may be had to the accompanying drawings in which like reference characters in the several views denote like parts, and in which Fig. 1 is a face view of the combination switch of my invention; Fig. 2 is a right side elevation of Fig. 1;

Fig. 3 is a rear view of Fig. 1; Fig. 4 is an interior rear view of the mechanism with the base removed;

Fig. 5 is a side view of the combination switch of my invention with parts broken away to clearly illustrate the mechanism;

Fig. 6 is a sectional view along the line 6—6 of Fig. 4;

Fig. 7 is a face view of the base illustrating the contact arrangement of the ignition and lighting units of the switch;

Fig. 8 is a view of the interior mechanism, part of the apparatus being removed to more clearly show the locking arrangement, the switch units being at normal and unlocked;

Fig. 9 is a view similar to Fig. 8 showing the locking mechanism in its operated position;

Fig. 10 is a rear view of the switch showing a protective relay supported on the base in place of the fuse as illustrated in Fig. 3;

Figs. 15 and 16 are partial sectional views of one of the studs which secures the escutcheon supporting plate and enclosing casing together, Fig. 15 showing the stud after the stud has been inserted in position to secure the plate member and casing together;

Fig. 17 is a sectional view along the line 17—17 of Fig. 7;

Fig. 18 is a sectional view of the horn button which may be substituted in place of the cowl light unit and

Fig. 19 is a disassembled perspective view of the lever and its associated parts.

Referring now in general to my invention, as illustrated in the accompanying drawings, it comprises a lighting switch unit L and an ignition switch unit M. The light switch unit L has a normal or off position A, and three operative positions B, C and D which

switch unit L, when in these different operative positions will close circuits to effect the lighting of certain lamps of the automobile. The ignition switch unit M has a normal or off position E, in which position the ignition apparatus is rendered inoperative, and an operative position F. When the switch unit M is moved to its operative position F the ignition circuit is closed and is thus rendered operative.

I also provide locking mechanism which consists preferably of a pin tumbler cylinder type lock T, which controls a sliding plate member S which is adapted to lock the ignition switch unit M only in its off position E. The sliding locking plate member S is also associated with the lighting switch unit L and is adapted to lock the lighting switch unit L in its "off" position A and its first two operative positions B and C. The lock T and its associated sliding locking plate S are so arranged that the key of the lock T can only be removed from the cylinder of the tumbler lock T when the switch unit M is in its "off" position E and when the lighting switch unit L is in its "off" position A or either of its first two operative positions B and C. The key however, cannot be removed when the ignition switch unit M is in its "ignition" or position F or if the lighting switch unit L is in its position D, so that should the operator attempt to remove the key when the switch unit M is in its position F he will be immediately apprised of the fact that the ignition circuit is closed. If the operator has restored the ignition switch unit M to its off position E and permits the lighting switch unit L to remain in its position D in which the headlights are burning and an attempt to remove the key from the lock T it will immediately apprise him of the fact that the headlights are burning and that to remove the key, the lighting switch unit L must be moved to either of its positions A, B or C to permit the removal of the key from the lock T.

Referring now more in detail to the switch of my invention I will first describe the back structure of the same. The back structure comprises preferably a flat circular mounting disk or base 2 made of any suitable insulation material such as fibre or bakelite. A number of suitable contact members 3', 4', 5', 6', 7', 8', 9', 10', 11' and 12' are provided and are secured in suitable slots 13 provided in the base 2. Contact members 3', 4' and 5' are associated with the ignition switch unit M and contacts 6', 7', 8', 9', 10', 11' and 12' are associated with the lighting switch unit L. As each one of the contact members is secured to the base 2 in the same identical manner, a description of one which is typical of the others will suffice to give a clear understanding of the others. Referring now to Fig. 17 and assuming for the sake of explanation that the contact member shown is the contact member 5', it is stamped out of suitable conducting material such as brass. The base 2 which carries these contact members is provided with a slot 13 of a size to receive the reduced portion of the contact member 5'. The reduced portion of the member 5' now being described is inserted in its respective slot 13 with the shoulders 14 and 14' formed by the reduced portion 5' when the member 5' is in position in the slot 13 resting against the face 2' of the base 2. The reduced portion of the member 5' protrudes slightly beyond the face 2' of the base 2 and by means of a suitable tool, this protruding portion is shaped by means of a swaging operation. The edges 5' and 5' are swaged to secure the member 5' in its slot 13 against movement and the intermediate portion is formed to present an arcuate portion 5' which forms the contact 5' adapted to be engaged by the wipers W and W' associated with the contacts as will be more fully hereinafter described. The terminals 3' and 5' which extend up from the face 2' of the base 2 of which the contacts 3' and 5' are a portion, are provided to permit the connection of external conductors for which I provide a suitable tapped orifice 15 and suitable means having screw threaded engagement with the tapped orifice 15 to secure the external conductors to these terminal members 3' and 5'. A terminal 16 secured to the base 2 in a manner already described is provided with an integrally formed laterally extending portion 16' which is provided with a depending member 4 which fits in a slot 13, and its protruding portion is shaped as already described to form the contact 4'. The terminal 16 is connected with the contact 4' by this laterally extending portion 16' which connects the contact 4' associated with the ignition switch unit M to this terminal 16 which is the battery terminal as will be more fully hereinafter described.

The terminals 6', 7' and 10' which are integrally formed with the contacts 6', 7' and 10' extend up from the face 2' of the base 2 and form terminals to which the external conductors are secured as already described. The terminal 17 which is integrally formed with the contacts 8' and 9' serves as a terminal for the contacts 8' and 9' and the terminal 18 which is integrally formed with the contacts 11' and 12' serves as a terminal for the contacts 11' and 12' and these two terminals 17 and 18 form connecting means for the external conductors.

An enclosing casing for housing the rotor circuit closing elements K and K' associated respectively with the lighting unit L and the ignition unit M comprises a plate member 20 provided with a dished portion 20' which is adapted to receive an escutcheon or designating plate 21 which bears the names of the different positions to which the ignition and lighting switch units L and M may be

5 moved. A cup shaped member 22 is also provided, the bottom of which is provided with a pair of orifices and similar orifices in the plate member 20 and the escutcheon plate 21
10 are in alignment therewith and are adapted to receive ferrules 23 which secure the escutcheon plate 21 to the plate 20, and the means for securing the plate 20 and casing 22 together to form a unit structure will be
15 more fully hereinafter described.

10 The rotor circuit closing elements K and K' which are provided for the ignition and lighting switch units L and M are adapted to be rotatably supported within the cup shaped member 22, and as the rotor elements K and K' are similarly constructed and rotatably supported in a like manner, a description of one will suffice. The rotor element K which is associated with the lighting switch
20 unit L comprises a disk 25 which is supported between two pair of spring arms 26, 27 and 30, 31, and these spring arms 26, 27 and 30, 31 in association with the disk 25 are for purposes as will presently be described. The disk 25 is provided with a square orifice 34, the side 35 of the square orifice 34 being provided with a notch 36, and an operating lever 37 associated with the rotor circuit closing element K for rotating the same is provided with an integrally formed lever shaft 38 provided with a cylindrical portion 39 which when in position rests in the ferrule opening of its associated unit. The lever shaft 38 is also provided with a square portion
25 40 next to the cylindrical portion 39 the said square portion 40 being of a size to permit entrance into the square orifice 34 of the disk 25. The side 41 of the square portion 40 of the lever shaft 38 is provided with an integrally formed rib 42 which enters the slot 36 in the side 35 of the square orifice 34 in the disk 25 and this slot 36 in association with the rib 42 permits the lever shaft 38 to be inserted only one way so that the lever shaft 38
30 will be in its proper position to register with the indications on the escutcheon plate 21.

With the lever 37 and its lever shaft 38 in position as just described the same may now be locked in position against lateral movement and to this end I provide a novel locking arrangement to prevent the lever shaft 38 from moving laterally in the ferrule 23 and square orifice 34 in the disk 25. The portion of the lever shaft 38 which protrudes through the disk 25 is provided with a reduced cylindrical portion 43 which is provided with a pair of integrally formed lugs 44 and 45 diametrically opposite, the face 46 of the respective lugs 44 and 45 being provided with
35 ribs 47 and 48, which cooperate with a cup shaped locking member 49 to secure the lever shaft 38 against lateral movement. The locking member 49 is cup shaped in form, the bottom of which is provided with a central ori-
40 fice 50 and notches 51 and 52 in the orifice
45

50 diametrically opposite each other which cooperate with the lugs 44 and 45 on the lever shaft 38. Notches 53 and 54 in the orifice 50 in the bottom of the cup shaped locking member 49 at right angles to the notches 51 and 52 cooperate with the ribs 47 and 48 on the face 46 of the lugs 44 and 45 for purposes as will presently be described.

55 The unit structure which comprises the plate 20, escutcheon 21 and enclosing cup shaped member 22 which form the enclosing casing and the levers 37 and 37' of the lighting and ignition switch units K and K' when in position as just described are now supported in a suitable fixture to support the same to facilitate assembly. Now with the lever 37 of the lighting switch unit L in position, the cup shaped locking member 49 is slipped over the protruding end of the lever shaft 38 and positioned so that the notches 51 and 52 in the orifice 50 of the locking member 49 will register with the lugs 44 and 45 on the lever shaft 38. The notches 51 and 52 are of a size to permit the lugs 44 and 45 to enter and to thus permit the cup shaped locking member 49 to slip over the lugs 44 and 45 and permit its rim 55 to rest against the face 56 of the disk 25 with the reduced cylindrical portion 43 of the shaft 38 extending into the orifice 50 in the bottom of the cup shaped locking member 49. The depth of the wall 57 of the cup shaped locking member 49 is substantially equal to the space or distance between the face 56 of the disk 25 and the face 46 of the lugs 44 and 45 on the lever shaft 38. With the cup shaped locking member 49 in this position the same may now be moved to its locking position and for this purpose I provide a suitable socket wrench provided with a slightly tapered orifice and which wrench is placed over the cup shaped locking member. Downward pressure is now applied to the socket wrench causing the wrench to grip the cup member 49 and as the rim 55 of the locking cup member 49 rests against the face 56 of the disk 25 this downward pressure applied on the wrench forces the disk 25 down on the square portion 40 of the lever shaft 38 causing the spring arms 26, 27 and 30, 31 between which the disk 25 rests to be flexed. The cup member 49 is forced down until the face 58 of the cup member 49 is below the ribs 47 and 48 on the lugs 44 and 45 and when in this position the cup member 49 may be turned in either a clockwise or counter clockwise direction a quarter of a turn through the agency of the wrench. The quarter of a turn of the cup shaped locking member 49 places the slots 53 and 54 in the bottom of the locking member 49 in alignment with the ribs 47 and 48 on the lugs 44 and 45. Now when the locking member is in this position the pressure applied on the wrench is released and the spring arms 26, 27 and 30, 31 which were flexed due
60

105
110
115
120
125
130

to this downward pressure return to their normal position which of course carries the disk 25 which is supported between the spring arms up and this upward movement causes the ribs 47 and 48 on the lugs 44 and 45 to enter the notches 53 and 54 in the bottom face of the cup shaped locking member 49. With the cup shaped locking member 49 in this position the lever 37 is held or locked in position against lateral movement in the orifice in the ferrule 23 and orifice 34 in the disk 25 but the lever 37 and its associated disk 25 may be rotated to its different operative position as is readily apparent from the above description.

The rotor elements K and K' with which the levers 37 and 37' are associated are adapted to be rotated through the agency of the levers 37 and 37' to their different operative positions, and to connect the contact combinations of the switch units L and M to close particular circuits in their different operative positions. I provide contact wiper carrying disks 59 and 60 associated respectively with the lighting and ignition switch units L and M and as each of the wiper carrying disks 59 and 60 is of similar construction, the description of one will suffice.

The contact wiper carrying disk 59 associated with the lighting switch unit L comprises a disk 59 of suitable insulating material such as bakelite and upon which the wiper member W is supported. The wiper member W comprises a ring shaped member 61 provided with three angularly displaced integrally formed tongue extensions 62 which are adapted to enter aligned orifices 63 in the disk 59 by means of a force fit to secure the same to the disk 59 against displacement or movement. The ring shaped member 61 is provided with radially disposed wiper arms 64, 65, 66 and 67 and which are integrally formed therewith and which are provided with flared end portions 64', 65', 66' and 67' which are adapted to engage the contacts 6', 7' etc. of the lighting switch unit L secured in the base 2 as will be more fully hereinafter described. To associate the disk 59 and its supported wiper arms 64, 65, 66 and 67 I provide a slot 68 in the disk 59 which receives the integrally formed lugs 44 and 45 on the lever shaft 38 to support the disk 59 on the lever shaft 38. The slot 68 in association with the lugs 44 and 45 prevents movement of the disk 59 on the lever shaft 38. Now when the lever 37 is moved to any of its operative positions the disk 59 being supported as just described is rotated with the lever shaft 38 causing the wiper arms 64, 65, 66 and 67 to engage the contacts 6', 7' etc. of the lighting switch unit L in the base 2. The ignition switch unit is also provided with a disk 60 carrying wiper arms 70, 71, 72 and 73 which disk 60 when in position on the lever shaft 38' in a manner similar to that just described in connection

with the switch unit L is adapted to engage the contacts, 3', 4' etc. in the base 2.

In order to maintain the rotor elements K and K' in the positions to which they may be moved I provide a disk 25 associated with the rotor K, and a disk 25' associated with the rotor K' and these disks 25 and 25' are supported on the lever shafts 38 and 38' of the respective levers 37 and 37' of the rotor elements K and K' as before described and through the agency of suitable spring means hold the rotor elements K and K' in their different operative positions as will now be described. A pair of plate members 75 and 76 each provided with four laterally extending arms 26, 27, 28, and 29 and 30, 31, 32 and 33. The members 75 and 76 are placed in matched relation and secured in this position by means of screws 77 which pass through suitable orifices in the matched members 75 and 76 and which have screw threaded engagement with suitable tapped orifices in integrally formed lugs 78 and 79 in the bottom of the cup shaped enclosing member 22, to secure the said members 75 and 76 in position to the bottom of the cup member 22. The arms 26, 27, 28 and 29 of the plate member 75 and the arms 30, 31, 32 and 33 of the lower or bottom matched plate member 76 form pairs of arms 26 and 30, 27 and 31, 28 and 32, and 29 and 33, and these pairs of arms are formed to cause their free ends to come in close proximity. Thus the arms 26 and 30, and 27 and 31 of the respective plate members 75 and 76 cooperate with the disk 25 of the rotor element K and the arms 28 and 32 and 29 and 33 of the respective plate members 75 and 76 cooperate with the disk 25' associated with the rotor element K' for purposes as will presently be described.

The disk 25 of the rotor element K and the disk 25' of the rotor element K', when thus inserted between their associated pairs of arms, force the free ends thereof apart to place them under tension. The disks 25 and 25' are provided respectively with a plurality of orifices 80 and 81 which extend through the disks and the peripheral edges of the orifices 80 and 81 in the respective faces 80' and 80'', and 81', 81'' of the disks 25 and 25' are countersunk. The free ends of the pairs of arms 26 and 30 and 27 and 31 associated with the disk 25 of the rotor element K and the free ends of the pair of arms 28 and 32 and 29 and 33 associated with the disk 25' of the rotor element K' are each provided with dished concave end portions which cooperate with the orifices 80 and 81 in the disks 25 and 25'. The free ends of the pairs of arms between which the disk 25 of the rotor element K rests, align themselves with a pair of orifices 80 in the disk 25, the concave end portions of which rest respectively in the countersunk portions of the pair of orifices 80 in the respective faces 80' and 80'' of the disk 25. The free ends of the two pairs of arms between which the disk 25' of

the rotor element K' rests, align themselves with a pair of orifices 81 in the disk 25', the concave end portions of which rest respectively in the countersunk portions of the pair 5 of engaged orifices 81 in the respective faces 81' and 81² of the disk 25'. Now when the operating lever 37 of the rotor element K is rotated to move the disk 59 upon which the wipers 64, 65, 66 and 67 are secured to one of 10 its operative positions, to engage certain contacts 6', 7' etc. in the base 2 the disk 25 will also rotate which moves the pair of orifices 80 in which the free ends of the pairs of arms 26, 30 and 27, 31 were resting, away from these 15 free ends causing them to ride upon the portion of the faces 80' and 80² of the disk 25 between the orifices 80 thus forcing them apart to place them under further tension and as the next pair of orifices 80 advance toward these 20 free ends of the pairs of arms, the concave end portions of the arms will start to enter the next pair of orifices 80 in the disk 25 and when the crowns of the concave portion of the free ends of the pairs of arms pass the edge 25 of the countersink around the orifices 80 in the respective faces 80' and 80² of the disk 25, the tension of the arms will produce a snap action caused by the free ends of the pairs of arms entering the countersink of the next pair of 30 orifices 80 under the influence of the tension of the arms. The rotor element K will now be held in its adjusted position by the free ends of the arms 26 and 30, and 27 and 31 resting in the orifices 80, and from the above 35 description the rotation of the actuating lever 37 of the switch unit K' will cause the pairs of arms 28 and 32 and 29 and 33 associated with the switch unit K' to cooperate with the disk 25' to produce this snap action when moving 40 this rotor element K' from one position to the other.

To limit the degree of rotation of the rotor element K when moved to its "off" or position A and its extreme advanced position D 45 a tongue 85 integrally formed with the casing member 22 extends upward. The disk 25 is provided with a reduced peripheral portion 86 in its circumferential edge which portion 86 forms shoulders 87 and 88 which engage respectively the tongue 85 when in its off position A and in its position D to limit the movement of the rotor element K in these directions. The degree of movement of the rotor element K' is also limited by a tongue 50 89 struck up from the casing member 22 and shoulders 90 and 91 formed by a reduced peripheral portion 92 of the circumferential edge of the disk 25' engage respectively the tongue 89 when the rotor element K' is in its off position E or its advanced position F.

The rotor element K is adapted to be locked in its "off" position A and its first two operative positions B and C but cannot be locked in its third position D, and the rotor element K' is also adapted to be locked in

its "off" position E but cannot be locked in its "on" or ignition position F. To accomplish this I provide a sliding lock plate 95 resting against the bottom of the enclosing casing 22 and which lock plate 95 is provided with a bifurcated upper portion 96 which bifurcation is of a size to receive the lug 78 integrally formed in the bottom of the casing 22. The sliding lock plate 95 is also provided with a lower bifurcated portion 97 which bifurcation is also of a size to receive the lug 79 which is integrally formed in the bottom of the casing 22. These two lugs 78 and 79 which are in vertical alignment serve as guides for guiding the lock plates 95 in its vertical movement in its travel from a locked to an unlocked position or vice versa. The bridge 98 of the plate 95 between the two bifurcations 97 and 98 rests between the two lugs 78 and 79 and in cooperation with the lugs 78 and 79 limit the movement of the sliding lock plate 95 in its locked or unlocked position as will be more fully hereinafter described. The lock plate 95 is also provided with a pair of angular extensions 99 and 100 integrally formed with the plate 95, the extension 99 cooperating with notches 101, 102, and 103 in the peripheral edge of the disk 25 of the rotor element K to lock it only in its "off" position A and its operative positions B and C and the angular extension 100 cooperates with a notch 104 in the peripheral edge of the disk 25' of the rotor element K' to lock the same in only its "off" position E as will presently be described.

A tumbler lock T is associated with the sliding lock plate 95 and is supported in the casing 22 by means of a tongue projection 105 which is struck up from the bottom of the casing 22 and which tongue 105 extends up in a bifurcated extension 106 integrally formed with the barrel 107 of the lock T to prevent the lock as a whole from turning when the key is inserted into the cylinder 108 of the lock. The cylinder 108 extends forward through suitable aligned orifices in the casing 22 plate 20 and escutcheon 21 to the front face of the switch. The sliding lock plate 95 is provided with a depending hook member 109 which cooperates with a pin 110 secured to the forward end of the cylinder 108 of the lock T and assuming that the key is turned to lock the units K and K' and that they are both in their "off" positions A and E and the operator wishes to lock the rotor elements K and K' in these positions A and E the operator now inserts the key in the cylinder 108 of the lock T and causes the cylinder 108 to rotate. With reference to Fig. 9 of the drawing the cylinder 108 rotates in a clockwise direction and the pin 110 and cylinder 108 rotate until the pin 110 engages the edge 111 of the hook extension 109 and further rotation moves the sliding lock plate 95 vertically causing the angular ex-

tensions 99 and 100 of the plate 95 to enter the slots 101 and 104 in the respective disks 25 and 25' of the rotor elements K and K' and when the bridge 98 of the lock plate 95 engages the lug 78 further movement of the lock plate 95 is prevented which in turn will prevent further rotation of the cylinder 108 and pin 110 of the lock T in this direction, and the key is now in such position so as to 10 permit its removal from the cylinder 108 of the lock T. When the lock plate 95 is in this position as clearly illustrated in Fig. 9 with its extensions 99 and 100 extending into the slots 101 and 104 in the respective disks 25 and 25' of the rotor elements K and K' the said elements K and K' are locked in their "off" positions A and E. To unlock the rotor elements K and K' the cylinder 108 of the lock T is rotated in a counter clockwise direction through the agency of the key until the pin 110 in the cylinder engages the edge 112 of the hook extension 109 of the lock plate 95 and further rotation now causes the lock plate 95 to be moved down causing its angular extensions 99 and 100 to be withdrawn from the slots 101 and 104 in the disks 25 and 25' of the respective rotor elements K and K' and when bridge 98 of the lock plate 95 engages the lug 79 further movement of the 20 key is prevented and the key may be withdrawn.

From the above description it may be seen that the ignition switch unit M can only be locked in its "off" position E and the lighting switch unit L can only be locked in its "off" position A and its positions B and C and should an attempt be made to lock the units L and M when the unit L is in its position D and the unit M in its "off" position E the extension 25 of the lock plate 95 will engage the peripheral edge of the disk 25 and prevent a complete rotation of the key in cylinder 108 and prevent the key from being withdrawn. Should the attempt be made to lock the units 30 L and M when the unit L is in its "off" position A and the unit M is in its ignition or position F the extension 100 of the plate 95 will engage the peripheral edge of the disk 25 of the unit M and prevent a complete rotation of the key and cylinder 108 and thus prevent the key from being withdrawn so that the operator is provided with a positive check so that in order to lock the units L and M the unit L must be in any of its positions 35 A, B or C, and the unit M must always be in its "off" position E. It is also readily apparent that the unit L may be locked in any of its positions A, B or C as the slots 101, 102 and 103 are provided in the disk 25 of this unit L for this purpose, but it is also readily apparent from the foregoing description that the unit M must be in its "off" position E to permit the unit L to be locked in its "off" position A and its positions B and C. To hold the sliding lock plate 95 in either of its

locked or unlocked positions I provide a tongue projection 76' integrally formed with the plate member 76 which bears against the bridge 98 of the sliding lock plate 95 under tension and this frictional engagement between this tongue projection 76' and the face of the bridge 98 of the lock plate 95 holds the lock plate 95 in either of its positions against movement. 70

The cowl light control unit CL comprises 75 a leaf spring 120 which extends through a suitable slot 13 in the base 2 and extends approximately parallel with the base 2 its free end being just above the contact 121 in the base 2 but not in engagement therewith and 80 which leaf spring 120 through the agency of suitable actuating mechanism may be moved into engagement with the contact 121. The contact 121 is secured in the base 2 in the same manner as described in connection with 85 contacts 3' and 4' etc. and it is also provided, with a terminal 122 and as a detailed description has already been given of the contacts 3', 4' etc. a further description is not thought necessary. A shaft 125 rotatably supported 90 in an aligned orifice in the escutcheon 21, plate 20 and casing 22 extends into the casing 22 and a tripod 126 which is secured to the bottom of the casing 22 by suitable means is provided with a central orifice 127 into which 95 the shaft 125 extends and which orifice 127 serves as a guide for the shaft 125. A disk 128 secured to an intermediate enlarged portion of the shaft 125 by a suitable spinning operation rests between the tripod 126 and the bottom of the casing 22 and a spiral spring 129 around the shaft 125 between the tripod 126 and the disk 128 maintains the cowl button shaft 125 in its normal position as illustrated in the drawings. The disk 128 is provided with an angular hooked member 130 integrally formed with the disk 128 which cooperates with a ridge 131 in the face of the tripod 126 for purposes as will presently be described. 100

A button 132 is secured to the shaft 125 for actuating the cowl light control unit CL and to actuate this unit CL pressure is applied upon the button 132 to move the shaft 125 and its supported disk 128 in a downward 105 direction against the normal tension of the spring 129 with reference to Fig. 6 and this movement is limited by an angular extension 133 integrally formed with the disk 128 which engages the bottom face of the tripod 126 and permits only a limited movement of the shaft 125 and its supported disk 128 in that direction. The shaft 125 has secured to it in any suitable manner an insulation button 134 which engages the leaf spring 120 when depressed causing the free end of the leaf spring 120 to engage the contact 121 in the base 2 to close the cowl light circuit. The limiting 110 of this movement of the shaft 125 by the stop projection 133 on the disk 128 prevents undue 115

pressure being placed upon this leaf spring 120 to prevent the spring 120 from being flexed to such an extent that its free end will not contact with its associated contact 121 in the base 2. Now to maintain the shaft 125 of the cowl unit CL in its actuated position, to maintain the spring 120 in engagement with the contact 121, the button 132 secured to the shaft 125 is turned or rotated in a counterclockwise direction with reference to Fig. 4 to bring the hooked projection 130 of the disk 128 into engagement with the ridge 131 of the tripod 126 to lock the shaft 125 in its depressed position, and this hook 130 in association with the ridge 131 maintains it in this position against the jarring of the machine. To restore the cowl light unit CL and permit the free end of the spring 120 to disengage the contact 121, the button 132 is rotated in a clockwise direction until the hooked projection 130 of the disk 128 has disengaged the ridge 131 on the tripod 126 and when in this position the combined tension of the spring 129 around the shaft 125 and the flexed spring 120 forces the shaft 125 upward causing the button 134 in the end of the shaft 125 to disengage the spring 120 permitting the spring 120 to disengage the contact 121.

The plate 20 and cup shaped enclosing member 22 are secured by means of studs 135 and the four studs 135 which secure the enclosing casing 22 and the plate 20 together also provide means for securing the base 2 to the enclosing casing 22 and as the method of securing the plate 20 and casing 22 by means of these studs 135 is alike the description of one will suffice. The stud 135 is provided with a flat head 136 which rests in the countersink in the plate 20 and extends through an orifice 138 in this countersink 137. The stud 135 is provided with an intermediate enlarged portion 139 which is provided with wing members diametrically opposite. The bottom of the casing 22 is provided with a boss 141 which is provided with an orifice through which the stud 135 extends and slots 143 in the orifice register with the wing members 140 and permit the wings 140 to protrude through said slots 143 as clearly illustrated in Fig. 15. The countersink 137 in which the head 136 of the bolt 135 rests extends up into the boss 140 in the casing 22 and with the stud 135 and parts in position as just described, a suitable tool is placed over the stud 135 and by means of a suitable riveting operation the protruding wings 140 are upset. The riveting operation as applied also causes the head 136 of the stud 135 to be spread, to thus secure the stud 135 rigidly in position against lateral movement, and the wing members 140 which were upset in the slots 143 in the orifice prevent the stud 135 from turning and the upset head 136 of the stud 135 thus rivets the plate 20 and enclosing casing 22 together. The escutcheon 21 is secured to the plate 20

and its casing 22 by means of the ferrules 23 as before described to form a unit enclosing structure.

The studs 135 extend rearwardly into the casing 22 and the base 2 is provided with orifices 145 which register with the studs 135 which pass therethrough and permit the base 2 to rest against the peripheral edge of the casing 22. A pair of orifices 146 and 147 are adapted to receive the ends of the lever shaft 38 and 38' and serve as bearings for the shafts 38 and 38' when the rotor elements K and K' are rotated. An orifice 148 in the base plate 2 permits the end of the cylinder 108 of the lock T to rest therein. Nuts 149 having screw threaded engagement with the ends of the studs 135 protruding through the orifices 145 in the base 2 are turned down to clamp the base 2 against the edge of the casing 22. With the base 2 thus secured in position the tumbler lock T is clamped in position between the bottom of the enclosing casing 22 and the base 2 against lateral movement and the tongue 105 in association with the bifurcated end 106 prevents rotation of the lock T, and the operating levers 37 and 37' of the rotor elements K and K' are rotatable in the bearings formed by the ferrules 23 and the orifices 146 and 147 in the base 2.

The contacts 6', 7', etc. of the rotor element K are now in position to be engaged by the wiper arms 64, 65, 66 and 67 on the disk 59 supported on the lever shaft 38 of the rotor element K when the same is rotated through the agency of the lever 37, and the contacts 3', 4', etc. of the rotor element K' are also in position to be engaged by the wiper arms 70, 71, 72 and 73 on the disk 60 supported on the lever shaft 38' of the rotor element K' when the same is rotated through the agency of the lever 37'. The actuating levers 37 and 37' of the rotor elements K and K' when rotated to their different positions cause the wiper arms of the respective elements K and K' to engage certain combinations of contacts in the base 2 to close the circuits of the different lights of an automobile and the ignition system of the engine as is well understood.

As illustrated in Fig. 3 of the drawing I show fuse clips 150 and 151 secured respectively to the terminals 16 and 18 by means of suitable screws which have screw threaded engagement with suitable tapped orifices 15 in the said terminals. A suitable fuse 152 is inserted in the clips 150 and 151 and the leaf spring 120 which is associated with the contact 121 of the cowl light unit CL extends through a slotted orifice 13 in the base 2 and this extended portion is provided with a tongue extension 153 which is secured to the terminal 18. The terminal 16 to which the fuse clip 150 is secured is the terminal to which the external battery lead is secured and through the agency of the fuse 152 battery is extended to the terminal 18.

of the lighting switch unit L so that battery which is extended to the different light circuits due to the manipulation of the switch lever 37 passes through the fuse 5 for the usual protective purposes. The battery circuit to the cowl light unit CL also passes through the fuse 152 to the terminal 18 to which the leaf spring 120 of the cowl light unit CL is secured.

10 An overload relay OR of any suitable type may be substituted by the removal of the fuse clips 150 and 151 by connecting the terminals of the relay OR to the terminals 16 and 18 all of which is clearly illustrated in Figs. 10 15 and 11 of the accompanying drawings. The relay OR when substituted in place of the fuse 152 serves the same purpose but instead of opening the battery circuit should an abnormal current flow through the relay OR occur 20 it will vibrate and give the operator a signal.

A horn button unit HB may be substituted for the cowl light unit CL and comprises an inverted cup shaped member 160 which is provided with depending prongs 161 which are inserted in aligned slotted orifices in the escutcheon 21, plate 20 and enclosing casing 22 and the protruding ends are clinched over to secure the member 160 in position. 25 The button 162 of the unit HB is provided with a square stem 163 which is inserted in a square orifice 164 in the closed end of the member 160, and an actuating rod 165 secured to the square stem 163 extends through an 30 aligned orifice in the escutcheon 21, plate 20, and enclosing casing 22. A coil spring 166 around the rod 165 rests between the square stem 163 of the button 162 and the escutcheon 21 and maintains the button 162 in its normal 35 position. The end of the actuating rod 165 which extends into the enclosing casing 22 is provided with an insulation button 167 secured to it in any suitable manner and which is adapted to engage the leaf spring 120. A 40 wing 168 formed on the protruding portion of the rod 165 engages the face of the enclosing casing 22 and limits the movement of the rod 165 and button 162 in its movement when 45 restoring to its normal position through the agency of the restoring spring 166. The button 162 when depressed moves against the tension of the coil spring 166 and the downward movement of the button 162 is limited 50 by the face 170 of the button 162 engaging the end 171 of the member 160 so that the button 162 may only be depressed a limited distance 55 to cause the insulation button 167 to engage the leaf spring 120 and move it into engagement with the contact 121 to close the circuit 60 of the horn so that the leaf spring 120 will be not flexed out of shape. The square stem 65 of the button 163 moving in the square orifice 164 of the member 160 prevents turning of the button 162 and also serves as guiding

means for the button 162. The tongue extension 153 of the leaf spring 120 when used in connection with a horn button unit HB is disconnected from the terminal 18 and connected to the terminal 16 so that when the circuit of the horn is closed battery will flow 70 direct through the spring 120 and contact 121 to the horn without passing through the protective device.

The lighting and ignition switch as a whole is adapted to be mounted in the cowl of the 75 automobile and to this end the cowl of the automobile is provided with an orifice 180 in which the body of the switch rests and a tongue extension 181 integrally formed with the plate 20 registers with a notch 182 in the orifice 180 of the cowl as illustrated in dotted lines in Fig. 2 to prevent the same from turning in the orifice 180 in the cowl. A bracket 183 provided with a pair of orifices registers with the studs 135 which protrude through the base 2 of the switch and which studs 135 pass through the orifices and nuts 149 having screw threaded engagement with the studs 135 clamp the bracket 183 in position with the leg extensions 184 of the 90 bracket 183 engaging the rear face of the cowl thus clamping the switch as a whole in the cowl opening against movement. Spring members 185 are also secured to the bottom of the bracket 183 for holding additional 95 fuses 152 for reserve use.

While I have described and illustrated a preferred embodiment of my invention it is to be understood that I do not wish to be limited to the exact structure as shown and 100 described but aim to cover all such changes and modifications which may come within the spirit and scope of the appended claims.

Having described my invention what I claim as new and desire to secure by United 105 States Letters Patent is:

1. A switch of the character described including a front plate and a back plate, a pair of rotatable elements mounted between said plates, operating levers for said elements, a shaft for each of said levers extending through said front plate, said elements and said back plate, said shafts each having a pair of lugs, and means intermediate of the ends of said shafts including cup-shaped 110 members adapted to engage said pair of lugs for detachably locking said shafts against longitudinal movement.

2. A switch of the character described including a front plate and a base, a pair of rotatable elements mounted between said plate and base, operating levers for said elements, shafts for said operating levers extending through said front plate, said elements and said base, said shafts each having a pair of diametrically opposed lugs, and a lock member comprising a cup-shaped 120 member cooperating with the said diametri-

- cally opposed lugs intermediate of the ends of said shafts to prevent longitudinal movement of said levers.
3. A switch of the character described including a front plate and a base, a pair of rotatable circuit controlling elements supported between said plate and base, operating levers for said controlling elements, shafts for said actuating levers each having a pair of integrally formed diametrically opposed lugs and extending through said front plate, said controlling elements and said base, a locking member comprising a cup shaped member cooperating with said diametrically opposed lugs intermediate of the ends of said shafts to prevent longitudinal movement of said levers, and circuit closing members for said elements supported on said shafts.
4. A switch of the character described including a front plate and a base, a pair of rotatable circuit controller elements supported between said plate and base, contacts in said base associated with said controller elements, operating levers for said elements and a shaft for each of said levers extending through said front plate, said elements and said base, integrally formed diametrically opposed lugs for each of said shafts, and means intermediate of the ends of said shafts including a cup shaped member adapted to cooperate with said lugs for locking said shafts against longitudinal movement.
5. A switch of the character described including a front plate and a base, a pair of rotatable circuit controller elements supported between said plate and base, contacts in said base associated with said controller elements, operating levers for said elements, a shaft for each of said levers having a pair of integrally formed diametrically opposed lugs and extending through said front plate, said elements and said base, a lock member comprising a cup-shaped member cooperating with said diametrically opposed lugs intermediate of the ends of said shafts to prevent longitudinal movement of said levers, and members secured to said shafts forming means for holding the levers in adjustable position.
6. A switch of the character described including a front plate and a base, a pair of rotatable circuit controller elements supported between said plate and base, contacts in said base associated with said controller elements, operating levers for said elements, a shaft for each of said levers having a pair of integrally formed diametrically opposed lugs and extending through said front plate, said elements and said base, means intermediate of the ends of said shafts including a cup shaped member adapted to engage the said integrally formed lugs for locking said shafts against longitudinal movement, and circuit closing members supported on said shafts for engaging said contacts in said base, said circuit controlling elements being held in position by spring means.
7. A switch of the character described including a front plate and a base, a pair of rotatable circuit controller elements supported between said plate and base, contacts in said base associated with said controller elements, operating levers for said elements, a shaft for each of said levers extending through said front plate, said elements and said base, a lock member comprising a cup-shaped member cooperating with means including a pair of diametrically opposed lugs intermediate of the ends of said shafts to prevent longitudinal movement of said levers, spring means adapted to maintain said cup-shaped member in cooperation with said lugs, and for preventing any unauthorized rotation of said shaft, and circuit closing members supported on said shafts to engage the contacts by movement of said actuating levers, and a plate provided with integrally formed lugs cooperating with notches in the said rotatable circuit controller elements.
8. A switch of the character described including a front plate and a base, a pair of rotor elements supported between said plate and said base, two groups of contacts in said base, one for each of said rotor elements, operating levers for each of said elements, a shaft for each of said levers extending through said plate, said rotatable elements and said base, a lock member associated with means on said shafts for preventing longitudinal movement of said shafts, spring means adapted to maintain said lock member in association with said means on said shaft and for preventing any unauthorized rotation of said shaft, circuit closing members for each of said elements supported on said shafts for engaging its associated group of contacts in said base, and a slideable plate provided with integrally formed lugs cooperating with notches in said pair of rotor elements.
9. A switch of the character described including a front plate and base, a pair of rotatable elements supported between said plate and base, two groups of contacts in said base, one for each of said rotatable elements, an operating lever for each of said rotatable elements extending through said plate, said elements and said base, a lock member and lugs on said operating levers cooperating with said lock member to lock said levers against longitudinal movement, spring means adapted to maintain said lock member in cooperation with said lugs and to prevent unauthorized rotation of said shaft, and circuit closing members supported on said levers associated with its respective group of contacts adapted to engage said contact group by movement of said actuating levers.
10. A switch of the character described including a front plate and a base, a pair of

5. rotor elements, each having a plurality of operative portions supported between said plate and base, operating levers for said rotor elements, cup-shaped members adapted to engage pairs of lugs integrally formed on said levers to prevent longitudinal movement of said levers, a disk associated with each rotor element, a pair of plate members secured to said front plate, and spring arms extending 50 from said members engaging orifices in the faces in said disks to maintain said rotor elements in any of their operative positions and to maintain said cup-shaped member in engagement with said lugs.
10. 11. A switch of the character described including a front plate and a base, a pair of rotor elements each having a normal and an operative position, said rotor elements being supported between said plate and base, operating levers for said elements for moving said rotor elements to any of their operative positions, integrally formed diametrically opposed lugs for said levers, cup shaped members adapted to engage said lugs to prevent longitudinal movement of the levers, a disk associated with each rotor element, a pair of plate members secured to said front plate, spring arms extending from said members, a plurality of orifices in said disks, said spring 90 arms engaging orifices in the respective faces of said disks to maintain said rotor elements in their normal or operative positions and to maintain said cup-shaped members in engagement with said lugs.
15. 12. A switch of the character described including a front plate and a base, a pair of rotor elements supported between said plate and base, each element having a normal and an operative position, operating levers having a pair of integrally formed diametrically opposed lugs for said rotor elements, a cup-shaped member adapted to engage said lugs to prevent longitudinal movement of said levers, a disk associated with each rotor element, a shaft 100 for said lever extending through said front plate, said rotor element and said base, a pair of lugs on said shaft, a cup member provided with a pair of notches which register with said lugs, and means in said cup and on said lugs for locking said lever against longitudinal movement.
20. 13. In a switch of the character described including a front plate and a base, a rotor element mounted between said plate and base, an operating lever for said element, a shaft 105 for said lever extending through said front plate, said element and said base, a lug on said shaft, a cup member provided with a notch which registers with said lug, means in said cup and on said lug for locking said lever against longitudinal movement, and spring means for holding said cup member in locked position.
25. 14. A switch of the character described including a front plate and a base, a pair of rotor elements each having a normal and an operative position, said rotor elements being supported between said front plate and base, operating levers for said elements for moving 110 said rotor elements to their operative positions, a cup-shaped member having a pair of notches, diametrically opposed lugs on said operating levers, the notches in said members adapted to engage the said lugs to prevent longitudinal movement of said levers, a disk associated with each rotor element, a pair of plate members secured to said front plate, spring arms extending from said members, a plurality of orifices in said disks, said spring arms engaging orifices in the respective faces of said disks to maintain said rotor elements in their normal or operative positions, and a member provided with integrally formed lugs cooperating with notches in said pair of 115 rotor elements.
30. 15. In a switch of the character described including a front plate and a base, a rotor element mounted between said plate and base, an operating lever for said element, a shaft 120 for said lever extending through said front plate, said rotor element and said base, a pair of lugs on said shaft, a cup member provided with a notch which registers with said lug, means in said cup and on said lug for locking said lever against longitudinal movement, and spring means for holding said cup member in locked position.
35. 16. In a switch of the character described including a front plate and a base, a rotor element mounted between said plate and base, an operating lever for said element, a shaft 125 for said lever extending through said front plate, said element and said base, a lug on said shaft, a cup member provided with a notch which registers with said lug, means in said cup and on said lug for locking said lever against longitudinal movement, and spring means for holding said cup member in locked position.
40. 17. In a switch of the character described including a front plate and a base, a rotor element mounted between said plate and base, an operating lever for said element, a shaft 130 for said lever extending through said front plate, said rotor element and said base, a lug on said lever shaft, a cup member provided with a notch which registers with said lug, a rib on said lug, a notch in said cup which receives said rib to lock said lever against longitudinal movement, and spring means for holding said cup member in locked position.
45. 18. In a switch of the character described including a front plate and a base, rotor elements provided with actuating levers having integrally formed diametrically opposed lugs, wiper members supported by said levers, two groups of contacts secured in said base, lock members consisting of cup-shaped 135 members cooperating with means including

18. In a switch of the character described including a front plate and a base, a rotor element mounted between said plate and base, an operating lever for said element, a shaft 5 for said lever extending through said front plate, said rotor element, and said base, a lug on said lever shaft, a cup member provided with a central orifice and a notch which registers with said lug, a rib on said lug, and a 10 notch in said cup at right angles to the notch which registers with said lug and which receives said rib to lock said lever against longitudinal movement, and spring means for holding said cup member in locked position.
- 15 19. A switch of the character described including a front plate and a back plate, a pair of rotatable elements mounted between said plates, operating levers for said elements, a shaft for each of said levers extending 20 through said front plate, said elements and said back plate, and means intermediate of the ends of said shafts for detachably locking said shafts against longitudinal movement, said means including integrally formed diametrically opposed lugs having a ridge on one 25 of their faces on said shafts adapted to fit into notches provided in the members on said rotatable elements.
- 20 20. A switch of the character described including a front plate and a back plate, a pair of rotatable elements mounted between said plates, operating levers for said elements, a shaft for each of said levers extending through said front plate, said elements and 30 said back plate, means intermediate of the ends of said shafts for detachably locking said shafts against longitudinal movement, said means including members on said shafts adapted to fit into the members on said rotatable elements, and a spring for holding said 35 rotatable elements in their adjusted positions and for holding the members on said shafts in engagement with said rotatable elements.
- 40 21. A switch of the character described including a front plate and a base, a pair of rotatable circuit controller elements supported between said plate and base, contacts in said base associated with said controller elements, operating levers for said elements, a shaft for 45 each of said levers extending through said front plate, said elements and said base, means intermediate of the ends of said shafts including diametrically opposed lugs, formed integrally with said shafts, adapted to cooperate with notches in a cup-shaped member 50 for locking said shafts against longitudinal movement, and spring means cooperating with members detachably secured to said shafts for maintaining said levers in their 55 adjusted positions.
- 60 22. A switch of the character described including a front plate, a rotary element, a shaft extending through said front plate and said rotary element, locking means between said rotary element and said shaft including a projection and a notch for preventing rotation between said shaft and rotary element, a cup-shaped member having notches adapted to be engaged by said projection to prevent longitudinal movement of said shaft, and 70 spring means for holding said projection in said notches.
23. A switch of the character described including a casing including a disk provided with depressions, a lever for rotating said 75 disk, and a pair of springs having free ends extending into said depressions for holding said rotary element in adjusted position.
24. A switch of the character described including a casing, a lever provided with a 80 shaft extending into said casing, means associated with said shaft including a disk provided with depressions and a pair of springs having free ends extending into said depressions for maintaining the said shaft in adjusted 85 position, and a rotatable contact member fitting onto said shaft and adapted to be rotated thereby.
25. A switch of the character described including a casing, a lever provided with a shaft 90 extending into said casing, means associated with said shaft including a disk provided with depressions and a pair of springs having free ends extending into said depressions for maintaining the said shaft in adjusted 95 position, and a rotatable member fitting onto said shaft and adapted to be rotated thereby, a spring contact member secured to said rotatable member.
26. A switch of the character described including a casing, an operating member extending into said casing having a pair of integrally formed diametrically opposed projections, a rotatable disk provided with notches adapted to be engaged by said projections and thereby rotatably secured to said operating member by means of the said notches and projections, a contact spring provided with integrally formed members fitting into notches in said disk, and stationary contacts adapted to be engaged by said contact member. 100
27. A switch of the character described including a casing, an operating member extending into said casing having a pair of integrally formed diametrically opposed projections, a rotatable disk provided with notches adapted to be engaged by said projections and thereby rotatably secured to said operating member by means of the said 110 notches and projections, a contact spring provided with integrally formed members fitting into notches in said disk, and stationary contacts adapted to be engaged by said contact spring, said spring contact member forming 115 the means for holding said spring contact member in engagement with said disk.
28. A switch of the character described including a front plate, an operating member extending through said plate, a member se- 120
- 65 125
- 130

cured to said plate having an orifice adapted to receive said operating member, and a hook upon said operating member adapted to engage said first member to prevent the said operating member from rotating or moving longitudinally thereby holding said operating member in an operating position.

29. A switch of the character described provided with a back plate, terminals extending through said back plate, a stationary contact and a spring contact, said contacts adapt-

ed to be locked in operative position or to be automatically returned to normal position, an extension for said spring contact extending through said back plate and adapted to be connected to either one or the other of a pair of said terminals extending through said back plate.

Signed by me at Chicago, in the county of Cook and State of Illinois, this 24th day of November, 1924.

ERNEST A. BOHLMAN.
